ATTORNEY.

UNITED STATES PATENT OFFICE.

WILLIAM J. CUNNINGHAM, OF PHILADELPHIA, PENNSYLVANIA.

BOTTLE-STOPPER.

SPECIFICATION forming part of Letters Patent No. 583,211, dated May 25, 1897.

Application filed April 18, 1896. Serial No. 588,152. (No model.)

To all whom it may concern:

Be it known that I, WILLIAM J. CUNNINGHAM, a citizen of the United States, residing in the city and county of Philadelphia, State 5 of Pennsylvania, have invented a new and useful Improvement in Bottle-Stoppers, which improvement is fully set forth in the following specification and accompanying drawings.

My invention relates to bottle-stoppers and 10 their adjuncts; and it consists of a novel construction of the same whereby the initial movement which occurs in opening a bottle will cause the bail thereof to contact with a recessed lug mounted upon the stopper and 15 thus tilt the same to one side or the other, thereby greatly facilitating the act of opening said bottle.

It further consists of novel details of construction, all as will be hereinafter set forth, 20 and specifically pointed out in the claims.

Figure 1 represents a side elevation of a bottle-stopper embodying my invention and a portion of the neck of the bottle to which the same is applicable. Fig. 2 represents a vertical sectional view of Fig. 1. Fig. 3 represents a side elevation showing the position the stopper assumes initially in the act of opening the bottle. Fig. 4 represents a plan view of the stopper.

Similar letters of reference indicate corresponding parts in the several figures.

Referring to the drawings, A designates the neck of a bottle, and B designates the rubber portion of the stopper seated thereupon.

C designates the bail which holds the stopper in position and which can be supported and actuated in any suitable manner.

D designates that portion of the stopper embodying my invention, the same consisting of 40 the body E, which has the neck F depending therefrom, to which latter is attached the flange G, which is adapted to be seated in the rubber portion B of the stopper.

H designates upwardly-extending lugs 45 which are mounted upon the body E and are hollowed or recessed, as will be evident from Fig. 4.

J designates a passage extending through the neck F, which has passing therethrough a 50 supporting device K for the bail C, said device K consisting of wire which is bent at its

lower portion so as to have the lateral feet L, which are held in position between the flange G and the cavity in the portion B, while its upper extremities M are slightly curved or 55 bulged, so as to form a seat for the reception of the bail C, as will be understood from Fig. 2, said extremities M being contained within the recessed lugs H, as will be evident from Fig. 4.

N designates shoulders formed in said lugs H, against one or the other of which the top of the bail C will contact in the initial act of opening the bottle, as will be evident from Fig. 3, whereupon it will be seen that the gas 65 contained within the same can readily escape and thus greatly facilitate the opening of the bottle.

The operation is as follows: The initial act of opening the bottle tends to elevate the bail 70 C, and the upper portion of the same will be caused to contact with one or the other of the shoulders N, and the stopper will be at once tilted or canted, as seen in Fig. 3, the effect of which will be evident.

Having thus described my invention, what I claim as new, and desire to secure by Letters Patent, is—

1. A bottle-stopper having a body portion, recessed lugs thereon, and a bail-support, the 80 arms of which are in the said recessed lugs.

2. A bottle-stopper consisting of the body portion B, the lug H rising therefrom, and provided with the shoulders N, the bail C, and the supporting device K therefor, the latter 85 having feet L, and the curved extremities M.

3. A bottle-stopper having a body portion, lugs thereon, shoulders on said lugs, and a bail-support having arms within said lugs.

4. A bottle-stopper having a body portion, 90 a bail-support suitably held, and lugs against which the bail is adapted to strike when released.

5. A bottle-stopper having a body portion, an inclosing rubber thereon, lugs on said body 95 portion, shoulders on said lugs, a bail and a bail-support within said body portion and held in place by said rubber.

WILLIAM J. CUNNINGHAM.
